UNITED STATES PATENT OFFICE

167,194

COMBINATION CLOCK AND RADIO RECEIVER CABINET

Robert D. Budlong, Skokie, Ill., assignor to Zenith
Radio Corporation, a corporation of Illinois

Application February 29, 1952, Serial No. 18,731

Term of patent 7 years

(Cl. D56—4)

To all whom it may concern:

Be it known that I, Robert D. Budlong, a citizen of the United States, residing at Skokie, in the county of Cook, State of Illinois, have invented a new, original, and ornamental Design for a Combination Clock and Radio Receiver Cabinet, of which the following is a specification, reference being made to the accompanying drawing, forming a part thereof.

The single figure is a perspective view of a combination clock and radio receiver cabinet showing my new design.

The design of the side not shown is similar to the design of the side shown. The rear portion of the cabinet, not shown, is open. The dominant features of my design reside in the portions shown in full lines.

I claim:

The ornamental design for a combination clock and radio receiver cabinet, as shown and described.

ROBERT D. BUDLONG.
